UNITED STATES PATENT OFFICE.

FRANK G. SCOTT AND GEORGE L. SCOTT, OF NEWPORT, RHODE ISLAND.

PIPE-HANGER.

SPECIFICATION forming part of Letters Patent No. 448,550, dated March 17, 1891.

Application filed October 30, 1890. Serial No. 369,793. (No model.)

To all whom it may concern:

Be it known that we, FRANK G. SCOTT and GEORGE L. SCOTT, of Newport, in the county of Newport and State of Rhode Island, have 5 invented a new and Improved Pipe-Hanger, of which the following is a full, clear, and exact description.

Our invention relates to devices for hanging pipes to and along the walls, ceilings, or 10 floors of buildings, or in underground conduits or subways or other localities, and has for its object to provide simple, inexpensive, and efficient hanger devices of this character whereby pipes of any size may be put up by 15 pipe-fitters, plumbers, tinsmiths, or other workman without the aid of a blacksmith, and so as to be substantially supported and present a neatly-finished appearance.

The invention will first be described, and 20 then will be particularly defined in claims hereinafter set forth.

Reference is to be had to the accompanying drawings, forming a part of this specification, in which similar letters and numerals 25 of reference indicate corresponding parts in all the figures.

Figure 1 is a perspective view of the hanger-hook. Fig. 2 is a perspective view of the wall-plate by which the hook-holding rod is sus- 30 tained. Fig. 3 is a central sectional view of the wall-plate with a portion of the hook-rod therein; and Figs. 4, 5, 6, 7, and 8 are views illustrating various uses of the pipe-hanger, which will be hereinafter more particularly 35 referred to in describing the invention.

The hook A and wall-plate B of the device are preferably made of malleable iron, and the rod C, which connects the hook to the wall-plate for various uses of the hanger, is 40 preferably made of ordinary wrought or rolled iron.

The hanger-hook A is made with a main curved or bent body portion a, provided with an end shank or head a', in which are pro- 45 duced by casting, boring, or otherwise two crossing holes or apertures a² a³, either of which is adapted to receive the rod C. The hole a² preferably ranges about parallel with an imaginary line touching the two ends of 50 the hook, and the hole a³ ranges, preferably, about at a right angle with the hole a², which latter is preferably countersunk at the inner

face of the hook, shank, or head, as indicated by the dotted lines at a⁴ in the drawings, to accommodate the upset head of the hanger-rod. The central part of the hook-body is made sufficiently thick to allow a hole or perforation a⁵ to be made in it about parallel with the shank-hole a², either of these holes a² a³ a⁵ being adapted to receive the 60 hanger-rod, as hereinafter more fully explained.

The wall-plate B is made with a central outward enlargement, which is longitudinally bored through at b, and is also transversely 65 bored through at b', and is also preferably countersunk at the back face at b² to accommodate the head c of the hanger-rod C in certain adjustments of the device. The wall-plate is also provided with backwardly-projecting spurs or teeth b³ b³, which are to be 70 driven into the wall or support to temporarily sustain the hanger and pipe prior to effecting the permanent fastening by means of screws, bolts, or nails driven through the holes b⁴ of 75 the plate into the wall or support.

The drawings represent several adaptations of the invention for supporting pipes ranging either horizontally or vertically, these being but examples of the marked utility of 80 the hanger device.

In Fig. 4 the wall-plate B is shown fixed to the side of a beam or other vertical wall or support 1, with the hanger-rod C passed through the hole b of the plate and headed 85 above the plate, while the hook A is sustained by the lower headed end of the rod, which passes through the hole a³ of the hook.

In Fig. 5 the hanger-rod C is passed through the transverse bore b' of the wall-plate, which 90 is fastened to a ceiling or overhead support 2, the hanger-rod being here also shown as passing through the bore a³ of the hook head or shank, which head rests upon the head of the rod, or it may be a nut threaded thereon. 95 This figure also illustrates by dotted lines how one or more extra hooks may be hung by their holes a³ onto one rod, the extra hook being shown swung to the opposite side from the lowermost hook; but these extra hooks 100 may be sustained at any desired height on the rod by simply chiseling or burring it to prevent downslip of the hook.

Fig. 6 of the drawings illustrates how a se-

ries of gutter-sustaining hooks A may be supported from a wall 3 by means of spikes or bolts C', passed through the hook hole or aperture a⁵ into the support, and the dotted lines in this view show how wall-plates B and hanger-rods C may be used simultaneously with the bolts or spikes C' to sustain a heavy pipe from both side and overhead supports.

Fig. 7 of the drawings shows how a bolt or spike C² may be passed through the hook-shank hole a² into a side wall or support 4 to sustain a pipe therefrom, and Fig. 8 illustrates how two of the hooks A may be fastened together to nearly encircle a pipe, and by means of a bolt D, passed through the shank-holes a³ of the hooks, this view also showing how two rods C³C³ are passed at one end through the holes a⁵ of the hooks and at the other end through the holes b' of the wall-plates to allow a heavy line of pipe to be supported from either the floor 5 or from a ceiling and at any desired distance therefrom, depending on the length of the rods.

We purpose making the hooks in various sizes for sustaining pipes of different diameters. Hence on any ordinary work it is only necessary for the pipe-fitter, plumber, or tinsmith workmen to carry a supply of the hooks and the wall-plates and suitable iron rods, from which the hanger-rods C C' C² C³ may be cut to any requisite length and afterward headed for use with the wall-plates and hooks, as circumstances may require, and this may be done in fitting up lines of pipes or gutters on any class of work without the aid of a blacksmith, thereby promoting economy of time and labor, and the work when done presents a far neater appearance than is possible when the ordinary strap-iron hangers held by nails, bolts, or screws are employed.

It will be noticed that the hooks A may be swung or turned to any angle to accommodate the range of the lines of pipe which they substantially support. Hence these hangers are adapted to sustain steam, water, or soil pipes however it may be necessary to run them along the floors, ceilings, side walls, or roofs of buildings, or for supporting pipes in underground conduits or subways, or in other situations for any purpose.

Having thus described our invention, what we claim as new, and desire to secure by Letters Patent, is—

1. A pipe-hanger comprising a hook having a head or shank provided with holes ranging at angles with each other, a rod adapted interchangeably to either of the holes to support the hook, and a wall-plate provided with holes ranging at angles with each other and adapted to receive and sustain the hanger-rod, substantially as described. 55

2. A pipe-hanger comprising a hook having a head or shank provided with holes ranging at angles with each other, and also having a lengthwise hole through its bent body portion, a rod adapted interchangeably to said holes to support the hook, and a wall-plate provided with holes ranging at angles with each other and adapted to receive and sustain the hanger-rod, substantially as de- 60 70

3. In pipe-hangers, the pipe-sustaining hook provided in its head or shank with holes a²a³, ranging about at right angles with each other, in combination with means, substantially as 75 described, for supporting said hook, substantially as described.

4. In pipe-hangers, the pipe-sustaining hook provided in its bent body portion with a lengthwise hole a⁵, in combination with means, substantially as described, for supporting said hook, substantially as described. 80

5. In pipe-hangers, the pipe-sustaining hook provided in its head or shank with holes a²a³, ranging about at right angles with each other, 85 and provided in its bent body portion with a lengthwise hole a⁵, in combination with means, substantially as described, for supporting said hook, substantially as described.

6. In pipe-hangers, the hanger-rod wall-plate provided with holes b b', ranging about 90 at right angles with each other, in combination with a rod C and a hook A, substantially as described.
